His Attorney.

UNITED STATES PATENT OFFICE.

WILLIAM FORREST BROWN, OF KANSAS CITY, MISSOURI.

NUT-LOCK.

1,401,757.

Specification of Letters Patent. Patented Dec. 27, 1921.

Application filed February 28, 1921. Serial No. 448,379.

To all whom it may concern:

Be it known that I, WILLIAM FORREST BROWN, a citizen of the United States, residing at Kansas City, in the county of Jackson, son and State of Missouri, have invented a certain new and useful Improvement in Nut-Locks, of which the following is a specification.

My invention relates to improvements in 10 nut locks.

The object of my invention is to provide a nut lock which is simple, cheap to make, easily applied and removed and which is efficient in operation.

15 The novel features of my invention are hereinafter fully described and claimed.

In the accompanying drawing, which illustrates my invention,

Figure 1 is a longitudinal vertical section view of my improved nut lock.

20 Fig. 2 is a cross section on the line 2—2 of Fig. 1.

Fig. 3 is a perspective view of the shell.

25 Fig. 4 is a longitudinal sectional view of a modification of my invention.

Fig. 5 is a cross section on the line 5—5 of Fig. 4.

Fig. 6 is a cross section view of another modified form of my invention.

30 Similar reference characters designate similar parts in the different views.

1 designates a polygonal sided shell adapted to be fitted on a polygonal sided nut 2, which is mounted on the threaded portion 35 of the bolt 3.

4 designates interlocking material, preferably cement, of a nature such that it may be placed in the shell 1 while in a plastic condition and will then set or harden. The 40 cement 4 embraces the threaded part of the bolt 3 and inwardly extending projections 5 which extend inwardly from the side walls of the shell 1. The outer end of the shell 1 has a hole 6 which is considerably larger 45 than the diameter of the bolt 3 and through which the cement may be inserted into the shell.

In applying the nut lock, the nut 2 is first tightened on the bolt 3, after which the 50 shell 1, filled, or nearly filled with cement 4 is slipped onto the bolt 3 and over the nut 2. Excess of cement will be forced outwardly through the hole 6.

The cement engaging with the threads of 55 the bolt and with the polygonal sides of the

shell 1 and with the projections 5 will hold the cement from turning on the bolt and in the shell 1, after the cement hardens. As the shell 1 will be held from turning by the cement, the nut will be held by the shell 60 from turning on the bolt.

If desired additional means for holding the cement from turning on the bolt may be provided. In Fig. 1 there is shown a pin 7 mounted in a hole in the threaded part of 65 the bolt and extending into the cement 4. The pin will hold the cement from turning on the bolt. The projections 5 will hold the shell 1 from slipping off the nut 2.

In Figs. 4 and 5 a portion of the threaded 70 portion of the bolt 3 is cut away, leaving a flat surface 8 on which the cement 4 rests. This serves to hold the cement from turning on the bolt.

In Fig. 6, the bolt is shown provided with 75 a longitudinal groove 9 into which the cement flows. After the cement hardens the portion of the cement in the groove 9 holds the cement from turning.

To remove or to loosen the nut 2, the 80 shell 1 is tapped sharply to break up the cement 4, which can then be worked out of the shell through the hole 6. The shell 1 may then be slipped from the bolt and nut, after which the nut may be loosened or removed. In the form shown in Figs. 1 and 2, the pin 7 must be removed in order to remove the nut from the bolt.

85 For the interlocking material various substances may be used, as for example litharge 90 mixed with iron filings, but cement is preferable on account of its cheapness, quickness in hardening, and easy breaking quality, while at the same time it is sufficiently rigid and strong to hold the shell and nut from 95 turning under ordinary conditions of use.

I do not limit my invention to the structures shown and described, as other modifications, within the scope of the appended 100 claims, may be made without departing from the spirit of my invention.

What I claim is,

1. In a nut lock, a polygonal shell adapted to be fitted on a nut mounted on a bolt, the shell having one or more inwardly extending projections and being adapted to receive and hold plastic material in which a threaded portion of the bolt is embedded, substantially as set forth.

105 2. In a nut lock, the combination with a 110

- 5 bolt having a threaded portion and a nut mounted thereon, of a shell fitted on the nut and arranged to hold the latter from turning and having one or more inwardly extending projections, of interlocking material filling the shell and embracing a threaded portion of the bolt, said material being of a nature such that it will harden after having been placed in the shell, substantially as set forth.
- 10 3. In a nut lock, the combination with a bolt and a polygonal sided nut mounted thereon, of a polygonal sided shell fitted on the nut and encircling and spaced apart from the bolt and having one or more inwardly extending projections, and interlocking material filling the shell and embracing the bolt and said projections and being of a nature such that it will harden after having been placed in the shell, and means for holding said material from turning on the bolt, substantially as set forth.
- 15 4. In a nut lock, the combination with a bolt and a polygonal sided nut mounted thereon, of a polygonal sided shell fitted on the nut and encircling the bolt and spaced apart from the bolt and having one or more inwardly extending projections, and cement embracing the bolt and said projections in said shell, substantially as set forth.
- 20 5. In a nut lock, the combination with a bolt and a polygonal sided nut mounted thereon, of a shell fitted on the nut and encircling and spaced apart from the bolt and having one or more inwardly extending projections, cement embracing the bolt and said projections in said shell, and means for holding the cement, when the latter hardens,

from turning on said bolt, substantially as set forth.

6. In a nut lock, the combination with a bolt and a polygonal sided nut mounted thereon, of a shell fitted on the nut and encircling and spaced apart from the bolt and having one or more inwardly extending projections, cement in said shell embracing the bolt and said projections, and a pin mounted in the bolt and extending into said cement, substantially as set forth.

7. In a nut lock, the combination with a bolt and a nut, of a shell having means for engaging the nut to hold the latter from turning and encircling and spaced apart from the bolt, and material adapted to harden engaging the shell so as to hold the latter from movement, and engaging the bolt so as to hold the latter from turning, substantially as set forth.

8. In a nut lock, the combination with a bolt and nut, of a shell having means for engaging the nut to hold the latter from turning, and material adapted to harden interlocked with the shell and bolt, substantially as set forth.

9. In a nut lock, the combination with a bolt and nut, of a shell encircling and spaced apart from the bolt, and material in the shell and engaging the bolt and adapted to harden, the shell being arranged to hold the nut from turning, and the said material being interlocked with the bolt and shell, substantially as set forth.

In testimony whereof I have signed my name to this specification.

WILLIAM FORREST BROWN.
